(57) **CLAIM**

We claim the ornamental design for a foldably constructed pallet, as shown and described.

DESCRIPTION

FIG. 1 is a top isometric exploded view of a foldably constructed pallet in a first folded configuration. The pallet insert is shown in dashed lines for environment.

FIG. 2 is a bottom isometric exploded view of the foldably constructed pallet of FIG. 1 in the first folded configuration. FIG. 3 is a top isometric exploded view of the foldably constructed pallet of FIG. 1 in a second folded configuration. FIG. 4 is a bottom isometric exploded view of the foldably constructed pallet of FIG. 1 in the second folded configuration.

FIG. 5 is an isometric view of the foldably constructed pallet top of FIG. 1 in an unfolded configuration.

FIG. 6 is a top plan view of the foldably constructed pallet top of FIG. 5.

FIG. 7 is a bottom plan view of the foldably constructed pallet top of FIG. 5.

FIG. 8 is a front elevation view of the foldably constructed pallet top of FIG. 5.

FIG. 9 is a rear elevation view of the foldably constructed pallet top of FIG. 5.

FIG. 10 is a left side elevation view of the foldably constructed pallet top of FIG. 5.

FIG. 11 is a right side elevation view of the foldably constructed pallet top of FIG. 5.

FIG. 12 is an isometric view of the foldably constructed pallet bottom of FIG. 1 in an unfolded configuration.

FIG. 13 is a top plan view of the foldably constructed pallet bottom of FIG. 12.

FIG. 14 is a bottom plan view of the foldably constructed pallet bottom of FIG. 12.

FIG. 15 is a front elevation view of the foldably constructed pallet bottom of FIG. 12.

FIG. 16 is a rear elevation view of the foldably constructed pallet bottom of FIG. 12.

(Continued)

FIG. 17 is a left side elevation view of the foldably constructed pallet bottom of FIG. 12.

FIG. 18 is a right side elevation view of the foldably constructed pallet bottom of FIG. 12.

FIG. 19 is an isometric view of the foldably constructed pallet rails of FIG. 1 in a folded configuration.

FIG. 20 is a front elevation view of the foldably constructed pallet rails of FIG. 19.

FIG. 21 is a rear elevation view of the foldably constructed pallet rails of FIG. 19.

FIG. 22 is a left side elevation view of the foldably constructed pallet rails of FIG. 19.

FIG. 23 is a right side elevation view of the foldably constructed pallet rails of FIG. 19.

FIG. 24 is a top plan view of the foldably constructed pallet rails of FIG. 19.

FIG. 25 is a bottom plan view of the foldably constructed pallet rails of FIG. 19.

FIG. 26 is an isometric view of the foldably constructed pallet of FIG. 1 in a first assembled configuration; and, FIG. 27 is an isometric view of the foldably constructed pallet of FIG. 1 in a second assembled configuration.

The dashed lines in FIGS. 1-4 illustrate a pallet insert for environment and form no part of the claimed design. The dotted lines in FIGS. 5-7 and 12-14 represent fold lines of the claimed design.
